CLAIM

(22) Filed: **Aug. 25, 2010**

The ornamental design for headlamp for automobiles, as shown and described.

(30) **Foreign Application Priority Data**

Feb. 26, 2010 (KR) 30-2010-0008608

DESCRIPTION

(51) **LOC (9) Cl.** **26-06**

FIG. 1 is a front view of the headlamp for automobiles according to the present invention.

(52) **U.S. Cl.** **D26/28**

FIG. 2 is a rear view of the headlamp for automobiles of FIG. 1.

(58) **Field of Classification Search** D26/28-36;

FIG. 3 is a top view of the headlamp for automobiles of FIG. 2.

362/459-468, 475-478, 485-487

FIG. 4 is a bottom view of the headlamp for automobiles of FIG. 3.

See application file for complete search history.

FIG. 5 is a right side view of the headlamp for automobiles of FIG. 4.

FIG. 6 is a left side view of the headlamp for automobiles of FIG. 5; and,

FIG. 7 is a perspective view of the headlamp for automobiles of FIG. 6.
